(57) **CLAIM**

The ornamental design for a self-sealing corner trim, as shown and described.

DESCRIPTION

FIG. 1 is an isometric view of the self-sealing corner trim showing our new design;

FIG. 2 is a left side view of the self-sealing corner trim of FIG. 1, the right side view being a mirror image thereof;

FIG. 3 is a top view of the self-sealing corner trim of FIG. 1;

FIG. 4 is a front view of the self-sealing corner trim of FIG. 1;

FIG. 5 is a back view of the self-sealing corner trim of FIG. 1; and,

FIG. 6 is a bottom view of the self-sealing corner trim of FIG. 1.

The self-sealing corner trim is shown with a symbolic break in its length. The appearance of any portion of the self-sealing corner trim between the jagged break lines forms no part of the claimed design.
